UNITED STATES PATENT OFFICE

2,460,134

THERMOMETRIC ALARM SWITCH

Jonathan O. Lee, Richmond, Va.

Application September 6, 1945, Serial No. 614,766

1 Claim. (Cl. 200—141)

1

The instant invention pertains to thermo-metric alarm switches and its primary object is the provision of a switch or circuit breaker which is adapted to close a circuit to sound an alarm when a predetermined temperature is reached and which is adapted to close a second circuit to sound another alarm more audible than the first alarm when a higher predetermined temperature characteristic of fire is reached.

Another object of the invention is the provision of a switch which may be rendered inoperative before or after the alarm is sounded.

Other objects will appear from the herein-after description.

The invention consists of certain novel features of construction, combination and arrangement of parts, all of which will be hereinafter set forth and particularly pointed out in the claim.

In the accompanying drawings which form a part of this application, I have illustrated what I now consider to be the best form of my apparatus.

In the drawings:

Figure 1 is a front elevation of the preferred embodiment of my invention;

Figure 2 is a wiring diagram;

Figure 3 is a front view, partly in vertical section, of the thermo-metric tube and associated parts of my device;

Figure 4 is an enlarged transverse section taken substantially on a plane as indicated by the line 4—4 of Fig. 3;

Figure 5 is right-hand (Fig. 3) side view of a portion of the thermo-metric tube;

Figure 6 is a diametral detail section of such tube portion.

In the drawing in which like characters of reference designate like or similar parts, numeral 2 indicates a housing of metal, plastic or other suitable material to house all or parts of the apparatus constituting the preferred embodiment of my invention. This housing is provided upon the upper intermediate portion of its back side with eye means 3 whereby it may be suspended on the wall of a room. The upper portion of the front side of the housing has a plurality of slots 4 serving a purpose which will become clear as the description proceeds.

The front wall is also provided with an elongated rectangular slot 6 the edges of which are beveled and which serves as a window for giving the operator of the device to be described a full or sufficient view of a thermo-metric scale 9,

2

comprising parallel lines indicating a certain temperature of mercury 10 enclosed in a glass tube generally indicated by 12. The scale can be so arranged that every line thereon indicates a temperature five or ten degrees higher or lower than the next lower or higher line. The tube includes a spherical bulb 13, a lower tubular section 14 of relatively small cross section and an upper section 15 of larger cross section.

10 The cylindrical sections of the tube carry a series of aligned contacts 17, preferably of platinum, each including a pin portion 18 which extends through one of a series of holes in the tube formed on a line of the scale, and also including 15 an enlarged head 19 bearing against the tube. The tube is supported in the housing and behind the window in a suitable manner. The tube is surrounded above the bulb by the eye portion 21 of a holder 23 and at the top end by a similar 20 eye of a holder. A screw 24 is threaded into the eye and bears with its inner end against the tube to firmly clamp the same to the holder. The opposite end of either holder is formed into an eye 26. The lower end of a guide rod 29 is inserted in the right-hand (Fig. 3) eye of the lower 25 holder and supported therein by a flange 29. A similar guide is inserted with its upper end in the right-hand eye of the upper holder and depends therefrom in alignment with the lower 30 guide rod. The two adjacent ends of the rods are held in alignment by a sleeve 30 and separated from one another by a washer 31, both of insulating material.

A sleeve 33 is slidably disposed on the lower 35 rod and in electrical contact therewith and is part of a laterally extending contact portion 35 adapted to contact any of the contacts 17 and carrying an angular handle 36 extending around the lower guide rod and through a slot 37 in the 40 front wall of the housing. The handle terminates in a hand knob 38 disposed on the outside of the housing. A similar movable contact structure 33, 35, 36, and 38 is slidable on the upper rod. Each contact portion 35 carries near its free end 45 a semi-circular guide 39 slidable on the thermo-metric tube (Figs. 3, 4).

Upon the lower portion of the front wall are a pair of switches 49 either of which controls a circuit now to be described.

50 A battery or other source of current 42 is disposed in the housing or elsewhere and has one of its poles connected to one of the switches which is also connected to a buzzer 44. The same is connected by a conductor 45 to a fixed conduct- 55 ing sleeve 46 on the lower guide rod. A pin 47

extends through the wall of the bulb into the mercury and is connected on the outside by a conductor 48 to the other side of the battery.

One side of a second battery 50 is connected to the other 46 of the two switches which is also connected to an electric bell 52. The other side of the same is connected by a conductor 53 to a sleeve 54 on the lower end portion of the upper guide rod. A second pin 47 extends into the bulb and is connected on the outside by a conductor 55 to the other pole of the battery 50.

In order to operate the device the lower handle knob is manipulated so that its contact portion contacts the head of one of the pins having a scale number of the temperature which is to be announced. The upper hand knob is manipulated to set its contact on the head of the pin having a scale number of the fire temperature. The two switches are closed.

When the mercury in its expansion reaches the lower temperature for which the lower indicator has been set a circuit is completed. In this circuit the mercury bridges the left-hand bulb contact and the lower tube contact 35 and the buzzer is operated.

When the mercury reaches the upper scale number and fixed contact associated therewith on which the upper movable contact 35 is set, a circuit is closed which includes the upper fixed contact and the bulb contact to the right and sounds the bell indicating that the mercury has reached the scale number for fire temperature. The slots 4 render the sound of the buzzer and bell more audible.

While I have shown and described the preferred embodiment of my invention it is of course to be understood that I reserve the right to make such changes in the form, construction and arrangement of parts as will not depart from the spirit of the invention or the scope of the subjoined claim.

What I claim and desire to protect by Letters Patent is:

In a device of the class described, an expansible liquid thermo-meter including a bulb having a tube communicating therewith and rising therefrom, a series of longitudinally spaced terminal pins projecting through the wall of the tube of the thermo-meter above the bulb thereof and having contact heads exterior to the tube, a guide of electrical conducting material extending parallel to the tube, a movable electric contact slidably disposed on the guide and having a portion for selective engagement with the heads of the terminal pins, an arcuate guide element carried by the movable contact having portions disposed for engagement with the tube on either side of the heads of the terminal pins for maintaining said movable contact portion in position to engage the terminal pin head disposed on the same plane as the movable contact, and a conductor pin extending through the wall of the bulb and in constant contact with the expansible liquid for completing an electric connection therefrom to the first mentioned guide through the liquid and the terminal pin engaged by the liquid and movable contact.

JONATHAN O. LEE.
